UNITED STATES PATENT OFFICE.

JONATHAN HALEY, OF AKRON, OHIO, ASSIGNOR TO THE AKRON GLASS & MACHINERY COMPANY, OF AKRON, OHIO, A CORPORATION OF OHIO.

JAR OR BOTTLE PRESS.

SPECIFICATION forming part of Letters Patent No. 711,962, dated October 28, 1902.

Application filed November 20, 1901. Serial No. 83,014. (No model.)

To all whom it may concern:

Be it known that I, JONATHAN HALEY, a citizen of the United States, residing at Akron, in the county of Summit and State of Ohio, **5** have invented certain new and useful Improvements in Jar or Bottle Presses, of which the following is a specification.

My invention has relation to improvements in presses for forming jars, bottles, and analogous articles from molten glass, in which the article is first formed into a blank in a mold by a reciprocating plunger and is then transferred to a separable mold, by which its exterior is shaped and expanded therein by means **15** of a suitable fluid.

The objects of my invention are to produce a new and improved machine of the general class referred to which shall be simple in construction, rapid and effective in operation, **20** and one in which the operative parts shall be reduced to a minimum consistent with perfect work, and to provide simple and effective devices for opening and closing the blow and finishing mold, and to provide means for **25** regulating the movement of the different parts to avoid shock and jar to the machinery.

To attain these aforesaid objects, my invention consists in the peculiar and novel construction, arrangement, and combination **30** of parts hereinafter described and then specifically pointed out in the claims, reference being had to the accompanying drawings, which form a part of this specification.

In the accompanying drawings, in which **35** similar reference-numerals indicate like parts in the different views, Figure 1 is an elevation of my improved machine; Fig. 2, a side elevation of the lower portion of the same looking from the left of Fig. 1, with certain **40** portions in section; Fig. 3, an enlarged plan of the table, with parts above it in section in the plane of its top; Fig. 4, a section, enlarged, through the axis of a pair of molds, with certain parts in section; Fig. 5, a plan, enlarged, **45** of the separable neck-mold and associated parts; Fig. 6, an inverted plan of Fig. 5; Fig. 7, a plan, enlarged, of the plate that supports the blow-mold, showing the curved grooves that form ways for pins depending **50** from opposite halves of said mold to cause said halves to separate; and Fig. 8, an en-

larged detailed view of the spring-bolt for regulating the throw of the air-applying lever.

Referring to the figures, 1 is a table supported on side pieces 2, that rest on axles 3, **55** on the ends of which are mounted wheels 4 for facility of moving the machine about.

In the top of the table 1 are shallow grooves 5, extending transversely across its entire upper face, constituting ways for slidable **60** mold-bearing plates, to be described. On each side of the ways 5 arise from the tabletop 1 parallel rods 6, constituting guides for the vertically-reciprocating mechanism to be hereinafter described. These guides are **65** united and braced at the top by a yoke 7, having vertical internally-smooth openings centrally between the guide-rods 6, in which openings freely slide screw-threaded shafts 8, each bearing at its lower end a cross-head **70** 10. On the lower sides of these cross-heads 10 are plungers 9, and above the cross-heads **75** 10 are somewhat-similar cross-heads 11. The lower cross-heads 10 are secured upon the ends of the shafts 8 by screw-threads, and the upper cross-heads 11 are supported by nuts **80** 12 and 13, each bearing on either face of the cross-heads and are capable of being raised and lowered on the shafts 8 by rotation. Both of these cross-heads 10 and 11 have extended **85** side arms which fit and slide on adjacent pairs of the rods 6.

Surrounding each shaft 8 is a ring 14, retained above and below by nuts 15 and 16, meshing into the threads on the shaft, and **90** depending from these rings 14 are sliding rods 17, having heads that prevent their descent therethrough and which are secured at their lower ends in a rim mold-plate 18, constantly pressed downward both by their weight and by coiled springs 19, surrounding **95** the rods 17.

Secured at the bottom of the side pieces 2 and extending therebetween is a lower platform 20, on which centrally beneath each **100** shaft 8 is a cylinder 21, in which is a sliding piston, (not shown,) to which is connected a piston-rod 22, constituting a vertically-reciprocating engine, each cylinder being provided with a valve-chest 23 and an ordinary D- valve operating therein by means of a valve-rod 24.

Compressed air, which is generally the motive power used, is introduced into the valve-chests 23 from any convenient source through the inlet 25 and escapes in the usual manner.

5. There are also exhaust-ports 26, closed by safety-valves 27 on the stems 28, provided with detachable weights 29, by which the resistance may be regulated. From one side of each of the stems 28 projects a pin 30, arranged to engage a fixed collar 31 on the valve-rod 24, and thereby raise the valve-rod 24 and close the valve in the valve-chest and prevent the further entrance of air when the pressure overcomes the resistance of and 15 raises the safety-valve 27.

The piston-rods 22 are each secured to a cross-head 32 below the table 1, from the opposite ends of which extend vertically connecting-rods 33, passing up through the table 20 and which are secured in the upper cross-head 11. By this arrangement the cross-head 11 and its connected parts are reciprocated vertically on the guide-rods 6.

In the bottom of the shallow grooves 5 in 25 the table 1 is a slot 34, and in each of the grooves is a sliding plate 35, bearing a blank-mold 36 and a blow-mold 37. The blank-mold 36 consists of a metallic cup-shaped vessel in which the molten glass is placed and 30 pressed into the blank by descent of the plunger 9. This mold is externally reduced at the top to receive and fit the neck-mold, which is supported in a frame 38, slideable between guide-rods 6, and is sustained by rods 39, freely slideable in the cross-head 10, and these rods 39 have heads on their upper ends 35 to prevent their descent therethrough and are arranged to raise the neck-mold frame as the cross-head rises.

40. The neck-mold and its accompanying mechanism (shown enlarged in top and inverted plan in Figs. 5 and 6) embodies a frame 38, having a large central opening and having transversely across its upper face a dovetailed 45 way in which slide two plates having their inner adjacent ends cut away in a circular shape. The two halves 40 of the neck-mold are fastened to the inner cut-away ends of these plates and are arranged to slide to meet 50 and separate therewith, and in the lower face of the main frame 38 is a recess with ends cut in the arc of a circle concentric with the central opening of the neck-mold, in which is fitted a revolute plate 41, having a hole larger in size than said neck-mold. In opposite ends of the plates bearing the neck-mold are slanting slots 42, in which are arranged to slide bolts 43, depending from the under faces of said plates bearing the 55 neck-mold. The plate 41 has a handle 44, by which it may be partially rotated, by using which the halves of the neck-mold may be caused to approach and separate, as desired. The halves 40 of the neck-mold have such inner configuration as it is desired to give to the outside of the neck of the finished glass 60

article—as, for instance, a screw for a jar-cap.

The blow-mold consists of two halves 45, hinged together to form the body portion, and 70 the bottom 46 has a central depending peg that rests in a hole in the center of the plate 47. The plate 47 has two curved slots concentric with the hinge of the mold on opposite sides of the center and is itself supported 75 above the sliding plate 35 by four integral corner-blocks (indicated by dotted lines in Fig. 7) that rest on the sliding plate 35, and these parts—namely, the plate 47 and the plate 35—are held together by corner-bolts 80 48. The inner faces of these corner-blocks are curved to form a circular recess in which is a revolute plate 49, having slots, the ends of which nearest the center being in vertical alinement with the inner ends of the slots in 85 the plate 47, but the outer ends of which diverge therefrom, as indicated in dotted lines in Fig. 7. In the bottom of each half of the blow-mold is a depending pin 50, that enters the slots in the plates 47 and 49 when they 90 are in vertical alinement. Extending from one edge of the plate 49 is a short arm 51, adapted to alternately engage fixed blocks 52 95 66 as the plate 35 is pushed in one direction or the other, thereby turning the plate 49, and as a result the pins 50 will follow the coinciding parts of the slots in the plates 47 49 to open and close the halves 45 of the blow-mold as the plate 35 is pushed in one direction or the other, causing a partial revolution 100 of the circular plate 49, and thereby causing the halves, as before stated, of the blow-mold to open and close, following the movements of the sliding plate 35.

Rising from the top 1, adjacent to the guides 105 6 and the transverse grooves 5, are a number of revolute shafts 54, sliding on which are blow-arms 53. These arms are arranged to swing over the top of the neck-mold when it is at rest on top of the blow-mold and to fit closely 110 thereon and have through them longitudinal ducts connected at one end by flexible tubes 55 with a convenient source of compressed air and have at their free ends downwardly-opening spring-closed valves 56, arranged to lie 115 centrally above the article in the blow-molds and in vertical alinement beneath the plungers 9. To cause these blowing-arms to assume their position and to recede therefrom when the jar or bottle is complete, there are secured 120 to the lower ends of the shafts 54, beneath the table 1, crank-arms 57, wide at their free ends, in each of which there is a curved slot. (See Figs. 3 and 4.) From the bottoms of the sliding plates 35, centrally depending beneath the 125 blow-molds, are pins 58, that run in the slots in the crank-arms 57 and in the slots 34. Hence as the plates 35 are pushed in either direction to bring the blow-molds under the plungers 9 one end of the slots in the cranks 130 57 will encounter the pins 58 and rock the blowing-arms inward over the top of the neck-

mold when in proper position over the blow-mold.

In order to cause each blow-mold to assume its proper vertical position on its supporting-shaft 54, the following mechanism is employed: Projecting from the side of the frame 38, carrying the neck-mold, is an ear 68, perforated near its end to inclose the shaft 54, and as the blowing-arm is placed on the shaft 54, above this ear 68, it will be raised by each upward movement of the neck-mold frame 38. It may be found necessary in practice to interpose between the ear 68 and the blowing-arm on the shaft 54, as shown in Fig. 4, a collar 15 to insure the proper elevation of the blowing-arm in order to swing over the top of the neck-mold frame. To cause these several operations to be performed, there is journaled opposite each valve-chest 23 a rock-shaft 59, provided at its ends with levers 60 61, that extend to the front and back of the table 1 in convenient reach of the operator in their location. Secured to each of the rock-shafts 59 is a short arm 62, forked at its front end 25 to receive a pin 63 on the valve-rod 24, by which means the valve-rod and its valve are operated to actuate the piston and its rod to reciprocate the cross-heads and plunger. To guard against the stroke of the cross-heads 30 being given with too great an impulse and to act as a half-way stop, there is placed on the under front edge of the table 1 (on the left in Fig. 2) a stirrup 64, in which the lever 60 is permitted a limited vertical movement. This 35 stirrup 64 has projecting from one end of its inward side faces a notch to prevent the lever being moved to its full throw without an additional movement of the operator, and this stirrup is also provided at the bottom of 40 the slot therein with an adjusting-screw 69 to limit the downward movement of the lever 60. As a further guard for the same purpose as just stated there projects from the back of each of the rock-shafts 59 a rigid arm 65 (see 45 Figs. 2 and 8) in alinement with the lever 61, in which is a transverse spring-pressed bolt 67 with a rounded end arranged to engage a depression in the lever 61. This bolt is so arranged that its point will rest on the side 50 surface of the lever 61, when it is at the extreme limit of its throw in either direction, but will enter the opening in the lever 61 when it is between these limits.

In the drawings in Fig. 4 the completed 55 article is shown after the pressure of air has forced it against the inward sides of the separable or blow mold, the glass product being shown by solid cross-section lines and the mold 37 by broken cross-section lines.

The operation of the machine is as follows: 60 The plunger cross-head 10 is raised by admitting air into the cylinder 21 under the piston and the sliding plate 35 moved to bring the blow-mold 45 under the axial line of the 65 shaft 8. A suitable quantity of molten glass is then placed in the blank-mold 36, and the sliding plate 35 moved until the blank-mold

36 is directly under the plunger 9. The position of the D-valve in the valve-chest is reversed by either lever 60 or 61 causing the 70 plunger 9 to descend, which forces a portion of the glass in the blank-mold up into the neck-mold. The D-valve is then reversed and the plunger 9 rises from the blank-mold immediately followed by the neck-mold, 75 which as it leaves the top of the blank-mold will carry with it the blank. The plate 35 is then moved to its first position—namely, so as to bring this blow-mold 45 under the axial line of the shaft 8—in doing which the depending pin 58 in the bottom of the plate 35 will operate the crank 57, and thereby rotate the shaft 54 and swing the blow-arm over the top of the neck-mold and centrally below the plunger. Either lever 60 or 61 is then moved 80 by the operator, allowing air to enter over the piston in the cylinder 21, forcing down the plunger 9, the completed stroke of which is arrested by encountering the air-valve 56 on the blow-arm, which is thereby opened, 85 allowing the compressed air to enter the interior of the plastic blank in the blow-mold, thereby expanding it in all directions to assume whatever configuration is therein impressed. The operator then moves the handle 44, opening the neck-mold, and then by means of either lever 60 or 61 admits air under the piston in the cylinder 21, which raises the cross-head 10, leaving the completed article in the blow-mold. The plate 35 is then 90 moved until the blank-mold 36 is under the plunger 9, which by mechanism hereinbefore described opens the two halves of the blow-mold and permits a ready removal of the completed article therein. 105

Having thus described my invention, what I claim, and desire to secure by Letters Patent, is—

1. In a bottle and jar press the combination with a table having a sliding way in its face, parallel guides in opposite sides thereof, upper and lower cross-heads arranged to slide on said guides, a plunger-shaft bearing a plunger secured in one of said cross-heads, a rim mold-plate surrounding said plunger and sustained by rods slidable through a plate adjustably secured on said plunger-shaft, a neck-mold sustained by sliding rods in the lower cross-head, and having separable halves with means for closing and separating them, 110 of a sliding plate adapted to be moved across said table beneath said plunger, bearing a blank-mold and a separable blow-mold with means for closing and opening said blow-mold, and a reciprocating engine beneath said 115 table, having means to control the movements of said engine, substantially as shown and described.

2. In a jar and bottle press, the combination with a table having a sliding way in its 120 face and a slot beneath said way, and a plate arranged to slide in said way and bear molds and having a pin projecting through said slot, of a revoluble shaft extending through said

table bearing a blowing-arm arranged to swing over a neck-mold by the partial revolution of said shaft, and a crank-arm below said table having a slot to receive the pin of said plate to cause said blow-arm to swing over said neck-mold by the sliding of said plate, substantially as shown and described.

3. In a jar and bottle press the combination with a table and a guideway in the top thereof, a slidable plate moving in said guideway, and a blank-mold mounted on said plate, a blow-mold also mounted thereon consisting of two half-molds arranged to meet and register, a bottom adapted to fit and close said mold having a central depending pin, depending pins from each of said half-molds, a supporting-plate having a hole to receive said bottom pin, slots in said plate to receive said pins from the half-molds, a revoluble plate beneath said slotted plate, slots in said revoluble plate arranged to cross the slots in the upper plate, to also receive said pins, to cause the halves of said mold to separate and close by the partial turning of said revoluble plate, a projecting arm on one side of said revoluble plate and a pair of upright posts to one side of the herein-described mechanism to lie in the path of and actuate said projecting arm, and reciprocating-pressing mechanism to operate in connection with said molds, substantially as shown and described.

4. In a bottle and jar press having a table with a vertically-reciprocating plunger above said table, and a reciprocating engine below said table with connections to cause said engine to reciprocate said plunger, and a lever to control said engine of a stirrup supported by said table to inclose said lever, with a projecting tooth to encounter said lever and arrest its movement until turned aside, substantially as shown and described.

5. In a bottle and jar press having a table with a vertically-reciprocating plunger above said table and a reciprocating engine below said table with connections to cause said en-

gine to reciprocate said plunger, and a lever to control said engine having an indentation to receive the end of a bolt, of a spring-pressed bolt arranged to enter said indentation and arrest said lever until overcome by increased power applied thereto, substantially as shown and described and for the purpose specified.

6. In a machine of the class described, a bed-plate, plates arranged to slide upon said bed-plate, blank-molds carried by said plates, mating sections forming a bottle-mold, carried by said plates, means whereby said mating sections are automatically swung apart when the plates are moved upon the bed-plates, blowing-valves operating above the bottle-molds, cylinders, pistons and piston-rods beneath the bed-plate, means carried by the piston-rods of the cylinders for operating the blowing-valves, tubular connections to the cylinders for conveying air to the ends thereof and controlling-valves located in said connections, substantially as shown.

7. In a machine of the class specified, a bed-plate, sliding plates on said bed-plate, bottle-molds upon said sliding plates, blowing-valves operating above said bottle-molds, cylinders beneath the bed-plate, pistons operating in said cylinders, means carried by said pistons for actuating the blowing-valves, tubular connections for conveying air to the tops and bottoms of the cylinders, operating-valves located in said tubular connections for controlling the flow of the air above and below the pistons in the cylinders, and operating-handles for said valves, substantially as specified.

In testimony that I claim the above I hereunto set my hand in the presence of two subscribing witnesses.

JONATHAN HALEY.

In presence of—
C. E. HUMPHREY,
MAUDE ZWISLER.
